UNITED STATES PATENT OFFICE

133,978

DESIGN FOR A POURING SPOUT FOR CONTAINERS

William B. Johnson, United States Army,
Baltimore, Md.

Application August 19, 1942, Serial No. 107,960

Term of patent 3½ years

To all whom it may concern:

Be it known that I, William B. Johnson, United States Army, a citizen of the United States, residing at Baltimore, Maryland, have invented a new, original, and ornamental Design for a Pouring Spout for Containers, of which the following is a specification, reference being had to the accompanying drawing, forming part thereof.

Fig. 1 is a plan view of a pouring spout for containers, showing my new design, and

Fig. 2 is a side elevational view thereof.

I claim:

The ornamental design for a pouring spout for containers, as shown.

WILLIAM B. JOHNSON.
